Primary Examiner — Paula Allen Greene(74) *Attorney, Agent, or Firm* — Knobbe Martens Olson & Bear LLP(57) **CLAIM**

The ornamental design for a microphone stand, as shown and described.

DESCRIPTION

FIG. 1 is a first perspective view of the microphone stand embodying the new design;

FIG. 2 is a second perspective view thereof, illustrating the microphone stand in another configuration;

FIG. 3 is a left side view thereof;

FIG. 4 is a right side view thereof;

FIG. 5 is a back view thereof;

FIG. 6 is a front view thereof;

FIG. 7 is a top view thereof; and

FIG. 8 is a bottom view thereof; and,

FIG. 9 is a perspective view of the microphone stand embodying the new design, illustrated with an example attachment mechanisms.

Broken lines are used to illustrate features of the microphone stand that form no part of the claimed design.

1 Claim, 9 Drawing Sheets(56)
